STILL PICTURE PROJECTOR

Richard W. Lanigan, Evanston, Ill., assignor to Bell & Howell Company, Chicago, Ill., a corporation of Illinois

Application September 19, 1958, Serial No. 52,692

Term of patent 14 years

(Cl. D61—1)

FIG. 1.

I claim:

The ornamental design for a still picture projector, as shown.
